UNITED STATES PATENT OFFICE.

JACOB B. STRUBLE, OF WILKINSBURG, PENNSYLVANIA, ASSIGNOR TO THE UNION SWITCH AND SIGNAL COMPANY, OF SWISSVALE, PENNSYLVANIA, A CORPORATION OF PENNSYLVANIA.

RELAY.

No. 863,667.

Specification of Letters Patent.

Patented Aug. 20, 1907.

Application filed February 18, 1907. Serial No. 357,919.

To all whom it may concern:

Be it known that I, JACOB B. STRUBLE, a citizen of the United States, residing at Wilkinsburg, in the county of Allegheny and State of Pennsylvania, have 5 invented certain new and useful Improvements in Relays, of which the following is a specification.

My invention relates to relays, and especially to relays for use in railway signaling systems employing alternating current track circuits, whether such systems 10 are used on steam railways or on electric railways, wherein the track rails are included in the return path to the generator for the car propulsion current which may be either direct or alternating.

I will describe a relay embodying my invention and 15 its use in a signaling system for electric railways, the track rails of which are included in the return path for the car propulsion current.

In the accompanying drawings, Figure 1 is a vertical sectional view of a relay embodying my invention. 20 Fig. 2 is another vertical sectional view of the relay illustrated in Fig. 1. Fig. 3 is a diagrammatical view of a portion of an electric railway, the track rails of which are divided to form block sections and are included in the return path for the car propulsion current 25 and having applied thereto an alternating current signaling system embodying my invention.

Similar letters of reference designate corresponding parts in all of the figures.

R designates a relay. As here shown it comprises a 30 core r, which is substantially W-shaped, an energizing winding r¹ surrounding the middle leg r³ of the core, and an armature r², which is pivoted intermediate its ends upon the middle leg of the core.

r⁴, r⁵, designate the outside legs of the core, the end 35 portions of which form poles.

The core r and armature are laminated, and the armature r² is made comparatively heavy in order that it will not be vibrated or "chatter" on its pivots by the 40 alternating flux in the core due to an alternating current traversing the energizing coil. The armature r² is provided with a rectangular opening to receive the middle leg of the core, and this opening is of such size as to provide the same air space between each of the four 45 walls of the opening and the core of equal dimensions. The purpose of this arrangement is to avoid the vibration of the armature due to the passage of alternating lines of force from the middle leg to the armature. It will be evident that the pull exerted by these lines of force is equal in all directions and hence it is neutralized. The pivots for the armature are here shown as being adjustable screws r¹⁸ the pointed ends of which 50 enter non-magnetic (copper) bushing or bushings r¹⁹ provided in the middle leg r³ of the core.

r²⁰ designates a counterweight for the armature which 55 tends always to tilt or rock the armature on its pivots

in a direction to disengage or open the contacts controlled thereby.

r⁸ designates a closed conductor (which may be in the form of a copper ferrule) surrounding the leg r⁵, and r⁶, r⁷, pole pins of some non-magnetic material, for example, bone or brass, secured in the end faces of the legs r⁴, r⁵. The purpose of these pins is to regulate the amount of air gap between the armature and end faces of the legs r⁴, r⁵, and to prevent the armature from sticking, for any cause, to the end faces of the legs r⁴, r⁵. 60 The pole pin r⁶ projects beyond the end face of the leg r⁴ a greater distance than does the pole pin r⁷ from the end face of the leg r⁵, thereby providing a longer air gap between the end face of the leg r⁴ and the armature r², than between the end face of the leg r⁵ and the armature r². The difference between the two air gaps is equivalent in reluctance, to the reluctance offered by the closed conductor r⁸ with a low frequency current. The movements of the armature r² on its pivots 65 opens and closes contacts in one or more circuits. 70

r¹⁰ designates a suitable frame suitably pivoted to a framework provided for the parts of the relay. The frame r¹⁰ carries one or more contact springs r¹¹, which are insulated from each other and the frame. The end of the armature r² is connected by a link r¹² with the 80 frame so that as the armature moves the frame r¹⁰ moves with it.

r¹³ designates fixed contacts carried by a top r¹⁴ for a suitable casing r¹⁵ which receives the several parts 85 comprised in the relay.

The operation of the relay is as follows: The flux produced by an alternating current traversing the winding r¹, will have two paths in the core and armature; one path will be through the middle leg, the armature and the leg r⁴ and the other through the middle leg, 90 the armature and leg r⁵. The position of the armature with relation to the end faces of the legs r⁴, r⁵, will be dependent upon the relative amount of flux passing through the legs r⁴, r⁵, and the armature. In practice, the closed conductor r⁸, and the air gaps between the 95 armature and the legs r⁴, r⁵, are so proportioned that the armature will be balanced or will be attracted to the leg r⁵ when an alternating current of 25 cycles (propulsion frequency) traverses the winding r¹. Consequently, the relay in a signaling system applied to an 100 electric railway using an alternating current of 25 cycles or less for car propulsion current will not respond to the alternating propulsion current to close the signal circuit. I may state here, that when the armature is tilted on its pivot so that one end contacts with the pole pin r⁷, the contacts r¹², r¹³, are disengaged or opened. They will also be disengaged or opened when the armature is balanced on its pivots. The contacts r¹², r¹³, 105 are only engaged or closed when the armature is attracted to leg r⁴.

As is well known, the closed conductor r^8 will produce a counter-flux when cut by flux due to a current traversing the winding r^1 and this counter-flux at 25 cycles may be considered the equivalent of the reluctance caused by the excess air gap of leg r^4 . Consequently, the effect on the armature due to the 25 cycle current is neutralized or tends to cause a movement of the armature toward leg r^5 . If an alternating current of high frequency, (say 60 cycles) is traversing the winding r^1 , the closed conductor r^8 will offer a greater counter-flux than if an alternating current of lower frequency, (say 25 cycles) was traversing the winding r^1 , and the pole of the leg r^4 will be proportionally stronger. If now the alternating signaling current is of a high frequency, the armature will always be moved toward the leg r^4 to engage or close the contacts r^{12}, r^{13} . Of course, when the alternating signaling current is short circuited from the coil the armature will be moved by the counter-weight r^{20} to disengage or open the contacts r^{12}, r^{13} .

Referring now to Fig. 3, A designates a portion of an electric railway, which is divided by insulated joints to form block sections. As shown, both rails are provided with insulated joints to form block sections, though, if desired, only one such railway may be so divided. Both arrangements are well-known in the art. In the drawings I have shown one block section and portions of two others.

As the rails (one or both) are to be included in the return path for the car propulsion current, which, for the purpose of this invention should be alternating and of a low frequency, provision is made for conducting the propulsion current around insulation points by means of reactance bonds.

35 In the drawings I have diagrammatically illustrated what is known in the art as the balance type of reactance bond.

30 B, B^1 , B^2 , B^3 , etc. designate such bonds. The bonds, as is well known, comprise a core, a winding or 40 windings all the turns of which are in the same direction and in close inductive relation. Such a type of bond is illustrated in U. S. Patent No. 838 916, granted December 18th, 1906. In this type of bond the propulsion current is made to flow through two equal parts 45 of the winding or two windings of the same number of turns in reverse directions so that the propulsion current produces no magnetizing effect on the core of the bond. As shown, the windings of two adjacent bonds are connected by a conductor b or there may be a plurality of such conductors. By this arrangement of track the propulsion current in its return through the rails and the windings in the manner stated will not magnetize the cores of the reactance bonds, thus leaving them free to act as impedances for the alternating signaling current, which is of a higher frequency than the car propulsion current.

40 I have not illustrated the generator for the car propulsion current or the trolley or third rail, as these are well known in the art, and it may be either a direct or an alternating current generator.

The signaling system applied to the railway comprises a railway signal or signals for each block section,

and a track circuit for each block section to control one operation of the railway signal or signals. S designates one such railway signal.

65 Each track circuit comprises a source of alternating current and a relay. The source of alternating current to the track circuit of each block section is in the form of a transformer T, the secondary of which is connected with the track rails of the block section, while the primary thereof may be in multiple circuit with mains 20, 21, extending along the track from the generator G. If the signaling system is applied to an electric railroad using alternating current for propulsion purposes, the 70 alternating signaling current should be of a higher frequency than the frequency of the alternating current car propulsion current.

75 The operation of the system is as follows: With no train or car in a block section the parts will be in the positions indicated. When a car or train enters a block section, the wheels and axles thereof act as a short circuit for the alternating signaling current, and the winding r^1 of the relay being thus deenergized, the armature r^2 will move to open the contacts in the signal circuit and allow the railway signal to indicate that fact.

80 When the train or car moves out of the block section the parts are restored to the position shown. Should the propulsion current (if it be alternating) for any reason be caused to flow through the winding of the relay with the signaling current absent therefrom, it will not cause

85 the armature to move to close the signal current for the reasons hereinbefore stated. Should the car propulsion current be direct and the armature be in contact with the pole of the legs r^5 it will be held in that position owing to there being less air gap at that point than

90 between the armature and leg r^4 . If on the other hand direct car propulsion current traverse the winding when the armature r^2 is in contact with the pole pin r^6 , due to its being moved to that position by the alternating signaling current, and the alternating signaling current

95 should be short circuited from the winding, the two air gaps between the armature and the end faces of the legs r^4, r^5 will be about equal and the counter-weight r^{20} will move the armature to open the signal circuit.

100

105 What I claim as my invention is:

1. A relay comprising a core affording two magnetic paths, an energizing winding for said core, a pivoted armature for said core, and means for increasing the reluctance of one magnetic path over the other, whereby the armature will be moved on its pivot in response to the strongest magnetic circuit.

110 2. A relay comprising a W-shaped core, an armature pivoted to the middle leg of the core, an energizing winding for said core, and a closed conductor surrounding one leg of said core.

115 3. A relay comprising a substantially W-shaped core, an armature pivoted to the middle leg of said core, pole pins in the outside legs of the core for producing different size air gaps between the armature and the outside legs, an energizing winding for the core, and a closed conductor on one leg of the core.

120 In testimony whereof I have signed my name to this specification in the presence of two subscribed witnesses.

JACOB B. STRUBLE.
